**DISHWASHER WATER CIRCULATION
MECHANISM**

Myron E. Ullman, Jr., Canfield, and Jerry M. Harroff,
Salem, Ohio, assignors to Mullins Manufacturing Cor-
poration, Salem, Ohio, a corporation of Ohio
Filed Dec. 10, 1963, Ser. No. 329,422
13 Claims. (Cl. 137—563)

This invention pertains to the art of dishwashers and more particularly to a mechanism for circulating water in a dishwasher to accomplish the washing, rinsing and draining cycles by a single mechanism.

The invention is particularly adapted for circulating washing and rinsing water in a jet tower type of domestic dishwasher and it will be described with particular reference thereto; however, it will be appreciated that the invention has much broader applications and may be used for other domestic and institutional dishwashers and other analogous washing units.

A domestic dishwasher generally includes a cabinet for receiving dishes to be washed, a spray system for impinging water onto the dishes and two distinct water circulating mechanisms. The first mechanism is used to circulate water through the dishwasher cabinet during the washing and rinsing cycles and the second mechanism is used to drain the spent water from the cabinet between these cycles. In the past, these water circulating mechanisms for domestic dishwashers included a complex of valves, solenoids to actuate the valves, motors, pumps driven by the motors, and a complicated housing for enclosing these many elements. Due to the extreme complexity of the water circulating mechanisms heretofore used in domestic dishwashers, they have been quite expensive to manufacture and have been the most common source of failure during use of the dishwasher.

The present invention is directed toward an improved water circulating mechanism for a domestic dishwasher which substantially reduces the initial expense of manufacturing the dishwasher and decreases the probability of mechanical failure of the dishwasher during use. In addition, a dishwasher recirculating mechanism constructed in accordance with the present invention can be easily repaired in the home without requiring special mechanical skills or tools.

In accordance with the present invention, there is provided an improvement in a dishwasher water circulating mechanism comprising a cabinet having a lower sump, a recycling passageway communicated with the sump, a drain passageway, a valve means for selectively connecting the drain passageway with the sump, impeller means in the recycling passageway for pumping water from the recycling passageway into the cabinet, and impeller means in the drain passageway for exhausting water from the sump when the valve means is opened. The improvement of the mechanism as defined above as contemplated by the present invention comprises the provision of the recycling passageway directly below the sump and the drain passageway directly below the recycling passageway. The valve means for connecting the drain passageway with the sump is positioned between the two passageways so that water will flow from the sump into the recycling passageway when the valve is closed and, when the valve is opened, water will flow from the sump through the recycling passageway and into the drain passageway where it can be exhausted by the drain impeller.

In accordance with another aspect of the present invention, there is provided, in a dishwasher water circulating mechanism as set forth above, a further improvement which includes mounting the recycling impeller coaxially with respect to the drain impeller and coupling

2

both of these impellers to a single output shaft of one, non-reversible electric motor. In accordance with the preferred embodiment of the present invention, the common axis of the impellers is vertical and the motor is mounted above the recycling impeller so that water will not drain from the passageways into the interior of the motor, in the event of seal failure.

In accordance with still a further aspect of the present invention, a dishwasher water circulating mechanism as defined above is provided which includes a single housing, a single, nonreversible electric motor for driving the recycling impeller and the drain impeller and a single, externally actuated valve for controlling the operation of the circulating mechanism. This substantially reduces a complexity of the water circulating mechanism in a manner which will be hereinafter described in detail.

The primary object of the present invention is the provision of a dishwasher water circulating mechanism which is economical to manufacture, easy to install in a dishwasher and durable in use.

Another object of the present invention is the provision of a dishwasher water circulating mechanism which includes a single, non-reversible electric motor with the dual function of recycling the water through the dishwasher during the washing and rinsing cycles and, also, draining the water from the dishwasher between these cycles.

Still a further object of the present invention is the provision of a dishwasher water circulating mechanism which includes only one easily actuated valve for changing from the water recycling stage of the mechanism to the water exhaust or drain stage of the mechanism.

Yet another object of the present invention is the provision of a dishwasher water circulating mechanism which includes a single housing, a single drive motor and a single externally actuated valve that performs all of the functions of the heretofore more complex water circulating mechanisms for dishwashers.

These and other objects and advantages will become apparent from the following description used to illustrate the preferred embodiment of the present invention as read in connection with the accompanying drawings in which:

FIGURE 1 is a partially cross-sectioned, side elevational view of a dishwasher having a water circulating mechanism constructed in accordance with the preferred embodiment of the present invention;

FIGURE 2 is an enlarged, cross-sectional side view illustrating the preferred embodiment of the present invention;

FIGURE 3 is a cross sectional view taken generally along line 3—3 of FIGURE 2; and

FIGURE 4 is a partially cross-sectioned view taken along line 4—4 of FIGURE 3.

Referring now to the drawings wherein the showings are for the purpose of illustrating a preferred embodiment of the present invention only and not for the purpose of limiting same, FIGURE 1 shows a domestic dishwasher A having a substantially watertight cabinet 10 with a front access door 12, upper cover plate 14 and a truncated lower wall 16. The cabinet may be supported by any of a variety of structures; however, in accordance with the illustrated embodiment of the present invention, the cabinet is supported upon a lower mounting base 20. Dishes and other items to be washed are supported within the cabinet on movable racks 22, 24.

Water is directed into the cabinet 10 through a water inlet pipe 30 upon actuation of valve 32 by an appropriate electrical signal from a source which is not shown.

To prevent siphoning through inlet pipe 30, there is provided an anti-back siphon chamber 34 which operates in accordance with known principles. In spaced relation-

ship with respect to racks 22, 24 there is positioned a perforated jet tower 40 for impinging water supplied through line 42 onto the dishes supported on racks 22, 24. This water has an appropriate direction and velocity to clean all surfaces of the dishes. During the initial or washing cycle of the dishwasher, the water contains a detergent or other cleaning substance while clear water is used during the rinsing cycle. Water is exhausted from the cabinet 10 through a drain line 44 connected onto a water circulating mechanism 50 which mechanism forms the subject matter of the present invention.

This discussion of the structural details and function of dishwasher A is for the purpose of explaining the environment to which the present invention is particularly adapted; however, it is appreciated that various structural changes may be made within the dishwasher without affecting the function and general construction of mechanism 50. Basically, the mechanism 50 circulates water from the truncated wall 16, through the perforated jet tower 40, into the interior of cabinet 10 while the dishes are being washed or rinsed. Between these cycles, the mechanism 50 exhausts the spent water from the cabinet 10 through the drain line 44. The operation of mechanism 50 will be hereinafter set forth in detail.

A circulating mechanism 50 constructed in accordance with the present invention may take a variety of structural forms; however, there is illustrated in the drawings a preferred embodiment of the invention which has proven very satisfactory in use. The mechanism 50 includes a sump 52 connected onto the lowermost end of truncated wall 16 and having a generally funnel-shaped housing 54 with an upwardly facing shoulder 56 and an outwardly protruding annular flange 58. The junction between the wall 16 and the housing 54 is sealed by an annular seal 60 having an inner lip 62 molded to encompass flange 58 and an outer lip 64. To secure the junction between the wall 16 and housing 54, there is provided, in accordance with the illustrated embodiment of the present invention, a metal strap 66 of conventional construction. A pair of metal straps 68, similar to strap 66, are adapted to connect the sump 52 onto the upper portion of mechanism 50 as is best seen in FIGURE 1. The shoulder 56 supports a coarse mesh screen 70 which acts as a coarse filter adjacent the lowermost portion of truncated wall 16. The screen may be easily removed from the sump 52 for the purpose of cleaning.

Referring now to FIGURES 2 and 3, mechanism 50, constructed in accordance with the present invention, includes a single housing 80 having an upper housing portion 82, a lower housing portion 84 and a central partition 86 which combine to define an upper recycling passageway 90 and a lower drain passageway 92. These vertically spaced passageways are somewhat coextensive within the housing 80.

Adjacent the end of passageway 90 opposite sump 52, there is provided a recycling pump 100 having a housing 102 secured onto housing 80 by a plurality of spaced bolts 103. The housing 102 defines a pumping chamber 104 having an axial pump inlet 106 and a tangentially extending pump outlet 108 for directing water from the pumping chamber 104 into the water supply line 42 for ultimate use by the jet tower 40. The inlet 106 is defined by an opening 110 in the upper wall of housing portion 82 which opening receives a ring 112 having an upper inclined surface 114 defining the lower portion of pumping chamber 104. Within the pumping chamber there is provided an impeller 120 having a plurality of spirally positioned blades 122 with downwardly contoured surfaces substantially matching the inclined surface 114 of ring 112. The impeller 120 has an upwardly tapering, generally conical surface 123 which prevents the entrapment of air around the downwardly facing surface of impeller 120. This feature increases the efficiency of impeller 120.

Centrally positioned within the impeller 120 is a metal insert 124 which threadedly receives shaft 126 of a single,

non-reversible electric motor 128. The electric motor is mounted onto the pump housing 102 by a plurality of circumferentially spaced mounting posts 129. At the upper end of housing 102 there is provided a shaft seal 130 comprising a stamped metal cap 132 which is forced into opening 134 of pump housing 102 so that it will not rotate with respect thereto. Within the cap 132 there is provided a sealing boot 136 extending between the cap and a graphite sealing ring 138 which is biased downwardly by a spring 140 against a ceramic sealing ring 142 secured within the impeller 120 and around the insert 124. To secure the ceramic ring 142 with respect to the impeller, there is illustrated a resilient material 144. To energize motor 128 there is provided a starting relay 150 which is secured onto boss 152 of housing portion 82. The position of the relay 150 allows easy repair without dismantling the mechanism 50.

The recycling stage of the mechanism 50 can be appreciated from the structure so far described. Water enters 20 passageway 90 from sump 52 where it is pumped by impeller 120 through outlet 108 into the supply line 42 for reuse by the jet tower 40. The upwardly inclined surface 114 of ring 112 provides a gradually decreasing area to maintain the desired velocity gradient through the pump. 25 The motor 128 is positioned above the pump 100; therefore, there is no possibility of water leaking from the housing 102 into the interior of the motor 128.

Directly below the recycling pump 100 there is provided 30 a drain pump 160 having a pump housing 162 formed integrally with partition 86 as is best shown in FIGURE 2. The housing 162 forms an internal pumping chamber 164 having an axial inlet 166 communicated with the drain passageway 92 and a tangential facing outlet 168 communicated with the drain line 44.

35 In accordance with the illustrated embodiment of the present invention, the pump 160 has an impeller 170 with impeller blades 172. The impeller is best shown in FIGURE 3. Although only two blades are illustrated, it is appreciated that the impeller may take a variety of structural embodiments including more than two blades. The impeller 170 is driven by a shaft 174 having an upwardly extending extension shaft 176 with a cross section adapted to match the cross section of opening 178 in post 179 carried by the metal insert 124. The coupling between shaft 40 176 and opening 178 forms an axially slidable spline-like connection so that the vertical spacing between the impellers 120 and 170 is adjustable to accommodate various manufacturing tolerances in the housing 80.

45 Directly below the lowermost end of shaft 174 there is 50 provided a boss 180 integrally formed with respect to housing portion 84 and adapted to receive a metal bearing insert 182 which determines the vertical spacing of impeller 170 with respect to the pump housing 162. This insert extends above the top of boss 180 so that there is 55 no radial restraint imposed upon shaft 174 by the lowermost connection of the shaft. This construction greatly facilitates assembly and decreases the detrimental effect of variations caused by manufacturing tolerances. The impeller 120 is located within pump chamber 104 in a vertical position determined by the threadable connection between insert 124 and shaft 126 as is best shown in FIGURE 2. Since the vertical positions of the two impellers are determined by the motor shaft and the insert 182, the slidable driving connection between shaft 176 and 60 opening 178 compensates for stacking of tolerances from the lowermost portion of housing 80 to the uppermost portion of the housing. This is a distinct advantage in the construction of the dual impeller water circulating mechanism.

65 70 To seal the pump chamber 164 from the recycling passageway 90, there is provided a seal 190 having a generally annular cover 191 with appropriately positioned reinforcing ribs 192. Around the periphery of the cover 191 there is provided an outer annular seal 194 for sealing the housing 162 at the periphery of cover 191. A flexible

molded shaft seal 196 is provided with an outer lip 197 and a flexible boss 198 forming a large sealing surface with the shaft 174. The lip 197 is secured onto the cover 191 by an inner snap ring 199. The complete seal 190 is secured onto the partition 86 by a locking ring 200 with upwardly extending fingers 202 adapted to bite into the surfaces of the partition to provide a positive lock between the ring and the partition.

The advantages of providing two impellers driven by a single, non-reversible motor located vertically above the impellers have been mentioned in connection with the description of the preferred structural embodiment of the invention; however, it should be appreciated that the use of a single motor which simultaneously drives the two impellers eliminates the need for two separate motors or one reversible motor. In the prior art when a single motor was used for recycling the water in a dishwasher and for draining the water from a dishwasher, it was usually necessary to reverse the motor to accomplish this dual function. Such a construction was quite complex. This disadvantage has been completely overcome by the present invention since both impellers are continuously driven in the same direction by a single, non-reversible motor and the transition from the recycling stage to the drain stage is accomplished by a single externally actuated valve which will be hereinafter described in detail.

Referring again to FIGURE 2, the recycling passageway 90 is positioned directly above the drain passageway 92 and is generally coextensive therewith. The direction of water flow from sump 52 is determined by the position of a single valve 210 which controls communication between the vertically spaced passageways. Valve 210, in accordance with the preferred embodiment of the present invention, is positioned within opening 211 of partition 86 which opening is provided with a valve seat 212 on the lowermost side of the partition and tapering outwardly from the uppermost side of the partition for a reason to be hereinafter explained in detail. The valve 210 includes a valve body 214 having an upper integral shoulder 215 and a resilient valve lip 216 clamped between shoulder 215 and a ring 218. The ring is held in position on the valve body by a pin 220 extending between downwardly protruding lugs 222 on the valve body 214.

Valve 210 is actuated by an externally mounted actuator 230 comprising, in accordance with the preferred embodiment of the present invention, a solenoid 232 having a downwardly extending control arm or armature 233. The solenoid is provided with a mounting bracket 234 secured onto lug 236 at the sump end of housing portion 82 as is best shown in FIGURES 2 and 3. Extending in a generally horizontal direction there is provided a valve fulcrum rod 240 protruding into housing 80 through aperture 242 in housing portion 84. The fulcrum operation of rod 240 is determined by a swivel or pivot seal 244 formed of a molded resilient material which extends into a reduced portion 246 of fulcrum rod 240. To prevent displacement of the swivel seal 244, there is provided an externally secured plate 248.

The fulcrum rod 240 is biased into the counterclockwise position, as shown in FIGURE 2, by a compression spring 250 mounted within a bore 251 of lug 236 and secured onto the outwardly extending portion of rod 240. The innermost end 252 of rod 240 contacts pin 220 so that the spring 250 biases the valve body 214 upwardly with the lip 216 in sealing contact with downwardly tapering valve seat 212. The weight of the valve body 214 holds the pin 220 in contact with rod end 252 and the valve body can rotate less than 90 degrees because the lugs 222 extend downwardly a greater distance than pin 220.

In operation of the valve 210, the spring 250 holds the valve closed when the solenoid 232 is not actuated. In this position, water from sump 52 flows into recycling passageway 90 and is forced by pump 100 upwardly through the perforated jet tower 40. With the motor still rotating in the same direction, the solenoid 232 is actu-

ated to terminate the recycling stage and initiate the drain stage of the mechanism 50. With the solenoid 232 actuated, the rod 240 is pivoted in a clockwise direction as shown in FIGURE 2 so that the weight of valve body 214 opens the valve 210 to allow the water from sump 52 to pass through the recycling passageway 90 into the drain passageway 92 where it can be forced through drain line 44 by drain pump 160. Radially extending ribs 254 on valve body 214, best shown in FIGURE 3, are used to guide the movement of the valve body 214 within opening 211 as the rod shifts the valve 210 between the opened and the closed positions. The outwardly tapering valve seat 212 acts as a self-flushing arrangement for valve 210. Any large particles which enter the opening 211 will be flushed from the valve seat by the flow of water through opening 211.

From this description of the operation of valve 210, it is appreciated that the only control for selectively changing the cycle stage of circulating mechanism 50 is the actuation of valve 210. With the valve closed, the mechanism actuates to recycle water through the cabinet 10 and with the valve open, the mechanism 50 operates to drain the water from the cabinet. Such a construction greatly simplifies the control of the water circulating mechanism and, thus, reduces the manufacturing expense and the subsequent maintenance cost while using the mechanism for a prolonged period in a dishwasher.

In accordance with another aspect of the present invention, the valve body 214 is provided with an upwardly extending stand pipe 260 having a central opening 262 communicated directly with the drain passageway 92. The stand pipe extends through an opening in screen 70, not shown, and into a cabinet 10 adjacent wall 16. A plurality of apertures 264 in the uppermost end of the stand pipe 35 act as an overflow control for the cabinet 10. The apertures maintain a maximum water level 266 within the cabinet 10, as is best shown in FIGURE 1. If the water level within the cabinet tends to exceed the level 266, the water is drained through opening 262 into the drain passageway 92 where it is forced by pump 160 through the drain line 44.

During the drain stage of mechanism 50, the valve 210 is opened so that water is pumped from sump 52 out line 44; however, the pump 160 acts against a certain pressure head created within line 44. When the motor 128 is turned off, the pressure head forces water from line 44 back into the passageway 92. In accordance with the present invention, the volume of passageway 92 is so selected that it can generally handle the water forced back into the mechanism 50 by the pressure head on line 44; however, in some instances, the volume of water being forced back into the mechanism may exceed the volume of passageway 92. The excess water tends to increase the seal force between lip 216 and surface 212 so valve 210 acts as a backwash valve. In addition, the excess water progresses upwardly into opening 262 of the stand pipe 260. If it were not for the additional volume allowed by the stand pipe 260, the excess water within the drain passageway 92 could possibly be forced through seal 190 into the recycling passageway 90. If this should happen, the pump 160 would circulate stagnant water through the cabinet 10 during the next recycling stage of mechanism 50. This would tend to stain the dishes being washed. Consequently, the provision of the stand pipe 260 serves the dual function of limiting the water level within the cabinet 10 and preventing the accumulation of stagnant water in the recycling system of the mechanism 50.

Various other structural features of the water circulating mechanism 50 enhance its general operating characteristics. For instance, a plurality of arcuately positioned posts 270, as shown in FIGURES 2, 3 and 4, guard the axial inlet 166 of pump 160 from large items such as pits, particles off dishes, etc. Such large items can accumulate 70 in the bottom of passageway 92 for a prolonged time

without seriously affecting the operation of the mechanism 50.

Another structural feature of importance is the provision of a plurality of longitudinally extending reinforcing ribs 280 in passageway 90 which ribs are not only reinforce the partition 86 but also substantially decrease the turbulence of water flowing longitudinally through the recycling passageway. Thus, the water received by the pump 100 has somewhat laminar flow in the passageway 90. The partition 86 is provided with downwardly extending ribs 290 similar to ribs 280 in the recycling passageway 90. These ribs 290 are in the upper portion of the drain passageway; therefore, they have a somewhat lesser effect on the flow of water in drain passageway 92.

The assembly of the mechanism 50 as shown in the drawings is quite simple. First, the housing 80 is assembled by bonding the portions 82, 84 together with partition 86 secured therebetween. Thereafter, the seal 190 is positioned over shaft 174 and the impeller 170 is dropped into the chamber 164. Then, the lock ring 200 is forced into partition 86. In this manner, seal 190 is secured in place and the insert 182 determines the vertical position of impeller 170. The ring 112 is then bolted over opening 110 and impeller 120 is mounted onto shaft 126 of motor 128. The post 179 is thereafter slipped over extension shaft 176 so that the impellers 120 and 170 are drivingly secured together onto motor shaft 126. The pumps 100, 160 are assembled by bolting housing 102 onto housing 80.

The actuator 230 is assembled onto lug 236 with the rod end 252 extending below opening 211 in partition 86. Thereafter, the stand pipe 260 is forced through the opening 211 so that the rod end 252 contacts pin 220, as is shown in FIGURE 2. This completes the assembly of mechanism 50 so that it can then be attached to wall 16.

In general operation, the motor 128 is started by a relay 150 to commence the washing cycle. Thereafter, valve 32 directs water into cabinet 10 through pipe 30. This water is circulated through the perforated jet tower 40 to impinge upon the dishes on racks 22, 24. The water then accumulates in sump 52 where it is recycled through passageway 90 by pump 100. This operation is terminated by a timing device (not shown) after the dishes have been thoroughly washed. Thereafter the solenoid 232 is actuated which opens valve 210 so that the water is pumped from sump 52 out line 44 by pump 160.

After a preset time interval, the solenoid is again de-actuated which allows spring 250 to close valve 210. Then again, water is directed into the cabinet 10 by pipe 30 so that the rinsing cycle can be accomplished. The rinsing cycle is basically the same as the previously described recycling operation which was used to wash the dishes within the racks 22, 24 except no detergent or cleaning substance is used. After the rinsing cycle has been timed out, the solenoid 232 is again actuated to open valve 210 so that the rinse water within the sump 52 can be drained through line 44.

It is noted that control of mechanism 50 requires only the actuation of solenoid 232 to shift from the recycling stage of the mechanism to the drain stage. Such a control can be easily accomplished by a very inexpensive and durable timing device. The motor 128 is continuously rotating in the same direction during the complete operation of mechanism 50; therefore, there is no necessity for changing the speed or direction of rotation of the motor.

The present invention has been described in connection with a particular structural embodiment which has proven satisfactory in use; however, it is appreciated that the structural embodiment may be modified without departing from the intended spirit and scope of the present invention as defined in the appended claims.

Having thus described our invention, we claim:

1. A water circulating mechanism for a washing unit having a cabinet, a water spray device in said cabinet and a lower sump in said cabinet, said mechanism comprising a single, non-reversible motor, a recycling passageway communicated with said spray device, a drain passageway communicated to a drain outlet, a first impeller for circulating water through said recycling passageway, and a second impeller for exhausting water from said drain passageway, both of said impellers driven by said single motor, one passageway being vertically lower than the other, said higher passageway being communicated directly with said sump, and a single valve means in said higher passageway for selectively communicating said lower passageway with said higher passageway to by-pass flow from said sump into said lower passageway.
2. A mechanism as defined in claim 1 wherein said lower passageway is the drain passageway.
3. A mechanism as defined in claim 2 wherein said valve means includes a valve body movable downwardly to open said valve means, a valve seat having an outwardly tapering, downwardly facing, generally conical valve surface.
4. A mechanism as defined in claim 2 wherein said valve means includes a valve body and a stand pipe carried by said body to allow for excessive water drain back in said drain passageway.
5. A mechanism as defined in claim 2 wherein said drain passageway has a volume generally equal to or exceeding the volume of said water forced back into the mechanism through said drain outlet when said motor is de-energized.
6. A mechanism as defined in claim 2 wherein said drain passageway has a stand pipe to allow for excessive water drain back in said drain passageway.
7. A mechanism as defined in claim 6 wherein said stand pipe extends into said sump.
8. A mechanism as defined in claim 7 wherein said stand pipe has an upper opening to provide an overflow communicating said sump with said drain at all times.
9. In a dishwasher water circulating mechanism comprising a cabinet having a lower sump, a recycling passageway communicated with said sump, a drain passageway, a valve means for selectively connecting said drain passageway with said sump, impeller means in said recycling passageway for pumping water from said recycling passageway into said cabinet, and impeller means in said drain passageway for exhausting water from said sump when said valve means is opened, the improvement comprising: said recycling passageway being directly below said sump, said drain passageway being directly below said recycling passageway and said valve means being positioned between said passageways whereby water will flow into and through said recycling passageway when said valve is closed and will by-pass said recycling passageway and flow into said drain passageway when said valve is opened.
10. The improvement as defined in claim 9 wherein said valve means includes an aperture between said passageways, a valve seat around the periphery of said aperture, a peripheral valve element to selectively contact said valve seat to seal said drain passageway from said recycling passageway and a stand pipe extending upwardly into said sump, said stand pipe communicating said drain passageway with said sump and forming an overflow control in said sump.
11. The improvement as defined in claim 10 wherein said drain passageway has a volume generally equal to or exceeding the volume of water forced back into the mechanism when said motor is de-energized.
12. A water circulating mechanism for a washing unit having a cabinet, a water spray device in said cabinet and a lower sump in said cabinet, said mechanism comprising a single housing, a recycling passageway in the upper part of said housing and communicating said sump with

said device, a drain passageway in the lower part of said housing and communicated to a drain outlet, said passageways being generally coextensive in said housing, a pumping chamber in both of said passageways, said chambers being generally aligned in a vertical direction, an impeller in each of said pumping chambers for circulating water in the respective passageways, a single, non-reversible motor above said pumping chambers and secured to said housing, said motor having a single shaft for driving both of said impellers simultaneously, an opening communicating said passageways and remote from said pumping chambers, and a valve means for selectively closing said opening to control the operation of said mechanism while said motor is energized to drive said impellers.

13. A mechanism as defined in claim 12 wherein said drain passageway has a stand pipe extending into said

5 sump with an upper opening to provide an overflow communicating said sump with said drain passageway at all times.
